UNITED STATES PATENT OFFICE.

NATHANIEL S. SHALER, OF CAMBRIDGE, ASSIGNOR TO THEODORE A. DODGE, TRUSTEE, OF BROOKLINE, MASSACHUSETTS.

MAGNETIC FRICTION DEVICE FOR LOCOMOTIVES.

SPECIFICATION forming part of Letters Patent No. 333,554, dated January 5, 1886.

Application filed April 4, 1884. Serial No. 126,666. (No model.)

To all whom it may concern:

Be it known that I, NATHANIEL S. SHALER, of Cambridge, county of Middlesex, State of Massachusetts, have invented an Improvement in Magnetic Friction Devices for Locomotives, of which the following description, in connection with the accompanying drawings, is a specification, like letters on the drawings representing like parts.

Locomotives are usually provided with boxes for carrying sand or gravel, which may be delivered through pipes in front of the contact-point of the driving-wheels with the rail, in order to increase the friction or bite of the wheels, especially when the rails are wet or icy. This means for increasing the friction of the wheels is objectionable, from the fact that the sand is delivered very unevenly, it being frequently accumulated in small heaps upon the rail, so that several layers of the sand become interposed between the wheel and rail, and the sliding movement of one layer of particles upon another tends to diminish the friction, rather than increase it; and, furthermore, the pulverized material left on the rails increases the resistance of the train following the locomotive. The sand usually employed is silicious or flinty in nature, and is not sufficiently hard to cut into the metallic surfaces, so as to form a bond of union between them.

It has also been proposed to magnetize the wheels, so as to cause them to adhere more firmly to the rails, and also, in connection with such magnetized wheels, to use iron filings to increase the friction between the rails and wheels, and in connection with the apparatus for magnetizing the wheels and distributing the iron filings brushes have been employed to collect the filings on the rail near the point touched by the wheel. The best possible result is obtained by a single film of fine hard particles interposed between the rail and wheel-tread, so that each particle will act at its opposite sides upon the two metallic surfaces, cutting into them slightly, and thus forming, as it were, a bond of union between the two.

My invention has for its object to attain such most beneficial result; and it consists, mainly, in the employment of magnetic material—such as magnetic oxide of iron, or iron or steel fil-

ings—in connection with means for delivering the said material in the most effective condition at the contact-points of the rail and wheel, which is accomplished by magnetizing the latter and delivering the particles upon its periphery, so that they would be attracted and held thereon, and in the movement of the wheel will be conveyed to the contact-point, where they will operate to increase the friction to the largest possible extent.

The invention also consists in suitable appliances for magnetizing the wheels, delivering the magnetic particles thereon, and removing the crushed or pulverized material from the surface thereof after it has passed the contact-point with the rail.

Figure 1 is a side elevation of a portion of a locomotive provided with means for increasing the friction or bite of its wheels in accordance with this invention, and Figs. 2 and 3 details, showing devices for magnetizing the wheels.

The locomotive A, of any usual construction, is shown as provided with the usual sand-box, *a*, having delivery-pipes *b*, which preferably lead to the tread of the wheel at a point above its axle, instead of leading down to the track in front of the wheel, as has been heretofore commonly practiced. The sand-box *a* will be filled with magnetic material—such as pulverized magnetic iron ore, which is considerably harder than flint-sand, or, if desired, iron, or, preferably, steel filings may be used, or, in fact, any material which is composed of fine hard particles that will be attracted by magnetism.

In order to convey the said material to the point of contact between the rail *B* and wheel *W*, the latter is magnetized in any suitable way. Such magnetization may be accomplished by a series of strong steel magnets suitably connected with the tire of the wheel; or, preferably, the said wheel will have connected with its tire a number of iron or steel pins, *c*, (see Fig. 3,) constituting cores for coils *d* of wire, the terminals of which coils are connected by wire *e* with contact-rings *f f'* on the axle, the wheel by which the said wire and coils *d d'* may be placed in the circuit of a suitable electro-generator, *G*, shown as mounted on the tender and operated by a

belt from one of the axles of the said tender. The circuit-wires 2 3, from the brushes or current-collectors of the generator, are connected with contact-springs resting on the 5 contact-rings *f f'*, so that while the generator is operating with its circuit closed the tire of the wheel is magnetized, so as to attract and hold the particles issuing from the pipe *b*. The attraction of the wheel for the rail also 10 increases the holding power between them, and the magnetic particles sticking to the surface of the wheel will be carried by it down to the rail, and passing between the wheel and rail will tend to cut into or adhere more 15 strongly to each than the smooth surfaces of metals to each other, thus greatly increasing the holding power and neutralizing the effect of any material of a lubricating nature or having a tendency to diminish the friction or 20 holding power between the metallic surfaces.

In order to prevent the crushed and ground material that has passed between the wheel and rail, and has lost its biting or frictional properties to a large extent, from being again 25 carried to the point of contact, a suitable scraper or brush, *i*, may be employed to wipe over the tread of the wheel and remove such material therefrom. The pipe *b* will be provided with the usual valve to control the dis- 30 charge of material from the box *a*, and the

brush *i* may be properly arranged to be removed from the surface of the wheel, except while the magnetic material is being delivered. The circuit of the generator *G* may be provided with a switch to open its circuit, or 35 its armature-shaft may be disconnected from the actuating power when the holding power of the wheels does not need to be increased.

I claim—

1. A locomotive and receptacle for magnetic 40 gritty material thereon, combined with the drive-wheel, means to magnetize the same, and a delivery-pipe leading from the said receptacle to the periphery of the drive-wheel, substantially as described.

2. A locomotive and receptacle for gritty 45 or friction-increasing material, and the drive-wheel and means for delivering the gritty or friction material from the receptacle at its point of contact with the rail, combined with a cleaning device for removing the crushed material remaining on the wheel, substantially as described.

In testimony whereof I have signed my name to this specification in the presence of two 55 subscribing witnesses.

NATHANIEL S. SHALER.
